US00D913504S

(12) **United States Design Patent** (10) **Patent No.:** **US D913,504 S**
(45) **Date of Patent:** **** Mar. 16, 2021**

(54) **INJECTION-MOLDED PRODUCT**

(71) Applicant: **Mitsui Chemicals, Inc.**, Tokyo (JP)

(72) Inventors: **Takashi Yukita**, Chiba (JP); **Haruka Sugita**, Tokyo (JP); **Akira Hasegawa**, Chiba (JP); **Hideyuki Nagai**, Iwakuni (JP); **Yasufumi Tsuchiya**, Funabashi (JP)

(73) Assignee: **Mitsui Chemicals, Inc.**, Tokyo (JP)

(**) Term: **15 Years**

(21) Appl. No.: **29/683,214**

(22) Filed: **Mar. 12, 2019**

(57) **CLAIM**

The ornamental design for an injection-molded product, as shown and described.

DESCRIPTION

FIG. 1 is a top view of an injection-molded product showing our new design;

FIG. 2 is a bottom view of an injection-molded product thereof;

FIG. 3 is a front view of an injection-molded product thereof;

FIG. 4 is a rear view of an injection-molded product thereof;

FIG. 5 is a right side view of an injection-molded product thereof; and

FIG. 6 is a left side view of an injection-molded product thereof.

FIG. 7 is a perspective view of an injection-molded product showing thereof;

FIG. 8 is a top view of an injection-molded product showing our new design;

FIG. 9 is a bottom view of an injection-molded product thereof;

FIG. 10 is a front view of an injection-molded product thereof;

FIG. 11 is a rear view of an injection-molded product thereof;

FIG. 12 is a right side view of an injection-molded product thereof;

FIG. 13 is a left side view of an injection-molded product thereof; and,

FIG. 14 is a perspective view of an injection-molded product showing thereof.
